United States Patent Office

Des. 183,048
Patented June 17, 1958

183,048

BEVERAGE DISPENSER

Clare E. Hodgman, Mamaroneck, N. Y., assignor to The Coca Cola Company, Atlanta, Ga., a corporation of Delaware

Application April 18, 1957, Serial No. 45,787

Term of patent 14 years

(Cl. D2—3)

FIG. 3

Fig. 4 is a front elevation of the beverage dispenser.

The dominant features of the design reside in the portions shown in full lines.

I claim:

The ornamental design for a beverage dispenser, as shown and described.
